236,114

RODENT BAIT FEEDING BOX OR SIMILAR ARTICLE

Stanley Z. Baker, Cleveland Heights, Ohio, assignor to
J. T. Eaton & Company, Cleveland, Ohio

Filed Jan. 21, 1974, Ser. No. 435,271

Term of patent 14 years

Int. Cl. D22—06

U.S. Cl. D22—18

FIG. 1

FIG. 2

FIG. 3

FIG. 4

FIG. 5

FIG. 6

FIG. 1 is a perspective view of a rodent bait feeding box or similar article showing my new design;

FIG. 2 is a top view thereof;

FIG. 3 is a front view thereof;

FIG. 4 is a side view thereof;

FIG. 5 is a side view thereof of the side opposite that shown in FIG. 4; and

FIG. 6 is a bottom view thereof.

I claim:

The ornamental design for a rodent bait feeding box or similar article, as shown.
